FRANKLIN F. HALL AND RAY U. HALL, OF DEFIANCE, OHIO.

SEAT-SUPPORT.

1,118,762.

Specification of Letters Patent. Patented Nov. 24, 1914.

Application filed November 10, 1913. Serial No. 800,210.

To all whom it may concern:

Be it known that we, FRANKLIN F. HALL and RAY U. HALL, citizens of the United States, residing at Defiance, in the county of 5 Defiance and State of Ohio, have invented certain new and useful Improvements in Seat-Supports; and we do declare the following to be a full, clear, and exact description of the invention, such as will enable others skilled in the art to which it 10 appertains to make and use the same.

This invention is a shifting seat, adapted more especially for use on a vehicle whose frame is hinged or otherwise constructed so 15 that it tilts laterally from time to time; and the object of the same is to improve the construction of the support for such a seat. This object is carried out by the mechanism hereinafter more fully described 20 and claimed, and as shown in the drawings wherein—

Figure 1 is a rear elevation of a three-wheel corn planter provided with my improved seat support. Fig. 2 is a perspective view of the seat support on a slightly 25 larger scale. Fig. 3 is a sectional detail on the line 3—3 of Fig. 2. Fig. 4 is a longitudinal section through the seat, on the line 4—4 of Fig. 1.

30 In the drawings the letters W designate three wheels in the present instance which support a two part frame F and F' whose parts are hingedly connected as at H. We have shown this vehicle as typical of one 35 on which this improved seat support and seat may be used with advantage, and in fact we are using the same thereon at present; but we do not wish to be limited to this use of it.

40 Coming now more particularly to details of the present invention, the seat 1 may be of the pattern ordinarily employed on agricultural machines, and it is riveted or bolted at 2 to a strap iron 3 extending longitudinally 45 beneath it and provided at its extremities with upwardly opening hooks 4. These hooks loosely embrace parallel cross bars 5, preferably also made of strap iron standing on edge, and each cross bar has a raised 50 center as shown in Fig. 2 and depressed ends 6 preferably struck on ogee curves and terminating in forks 7. Set screws 8 may 55 pass through the bills of the hooks into the cross bars 5, whereby the seat proper may be adjusted laterally by moving its

strap iron 3 to the point most convenient for the driver.

Rising from each part of the frame and by preference inclining slightly to the rear, is a standard 10 which is herein shown also 60 of strap iron standing on edge, and in order to prevent the standard from swinging from side to side it is braced as at 11. Each standard carries a head which may be of casting or otherwise, and the head includes 65

a pair of arms 12 standing astride the standard and bolted as at 13 thereto, the arms being slightly spaced from each other and continued to the rear on a horizontal line into a slotted plate 14 with the rear end 70 of the slot closed as at 15. On this plate and overlying its slot rests a cap plate 16, and through the same pass the shanks of two eyebolts 17. Their eyes stand beneath the plate 14 and are loosely engaged with 75 links 18, and the lower ends of the latter are pivoted at 19 in the forks 7. These links by preference also are of strap iron, and as they fit closely but movably between the fork-arms, they prevent undue movement forward and backward of the cross bars 5, while their pivotal connection at 19 therewith and their pivotal support in the eyes of the eye bolts permits the longitudinal 80 movements of said cross bars transversely of the frame of the machine providing a flexible connection between the seat and frame to permit the frame sections to move transversely relatively to each other. 85

When this seat support is applied to any 90 machine and the same is tilted by reason of unevennesses in the ground, one pair of links swings outward and the other pair swings inward and the entire seat-supporting structure moves slightly toward the lower side. 95 With a three-wheeled running gear as illustrated in Fig. 1, if the intermediate wheel is raised there will be no effect on the seat support, but if either side wheel is raised the result will be the same as just described. By 100 preference we dispose the links 18 on a slight inclination toward the center as seen in Fig. 1, with the result that any lateral tilting of the machine frame causes the link on the lower side to move downward toward a vertical position while the link on the upper side is retarded in its movement inward to a still more inclined position, for the reason that its lower pivotal point 19 must of necessity rise. If both links stood strictly vertical 105 110

when the frame F was horizontal, this would not occur. By this arrangement of the links 18 with their lower ends converging toward each other, the vehicle to which 5 the seat is applied such as a corn planter is especially adapted for use in hillside plowing and going around and around a hill with the machine always at an inclination. When the machine is used for this purpose the seat 10 is adjusted on the cross bars toward the up hill side and when the operator is in position thereon his weight will tend to force the link on the up hill side downwardly in a vertical position and cause the other link 15 to move inwardly thereby raising the end of the cross bar carrying the seat and which is on the up hill side to properly position the driver. The upper ends of the braces 11 may be riveted at 20 to the arms of the 20 head, and it is not essential whether these rivets pass through the upper ends of the standards 10 or not. These and other details may be left to the manufacturer, and the materials and proportions of parts are 25 not essential.

What is claimed as new is:

A seat support comprising parallel laterally-spaced crossbars having ogee ends with

forked terminals, links pivoted at one end between said forks, longitudinally slotted 30 plates connecting both links at opposite ends of said crossbars, the slots of said plates being open at one end and closed at the other, a pair of downwardly and outwardly inclined laterally spaced arms at each end of 35 each of said plates, standards secured between said arms, cap plates, superposed on said slotted plates, and eye bolts, extending through said cap plates and the slots in plates on which they are mounted, the eyes 40 of said bolts being disposed, under said slotted plates and loosely engaged with the upper ends of said links, the pair of links at one end of said support converging at their lower ends toward the lower ends of 45 the pair of links at the other end of said support when said cross bars are in normal position.

In testimony whereof we have hereunto set our hands in presence of two subscribing 50 witnesses.

FRANKLIN F. HALL.
RAY U. HALL.
